ELECTRIC CONTACT ELEMENT

Alric H. Powell, Yeadon, Pa., assignor to General
Electric Company, a corporation of New York

Application May 6, 1942, Serial No. 441,894

1 Claim. (Cl. 200—147)

My invention relates to electric contact elements and particularly to means for extinguishing electric arcs between circuit breaking contacts. While not limited thereto the invention is particularly applicable to the contact of manually operable or other slow moving electric switches such as electric switches, controllers, and the like.

It is quite generally agreed that to interrupt quickly an electric arc it is necessary both to attenuate and to cool the arc. While magnetic means have long been used for attenuation without any special attempt to cool, and air blasts have been used for both attenuation and cooling, it is not known to provide a simple, self-centered and inexpensive magnetic structure which is effective both to attenuate and to cool an arc without the provision of special air blast means. Furthermore, prior magnetic blowout arrangements frequently permit concentration of the arc in the region of burnable insulating portions of the switch and its terminal connections.

One object of this invention is to provide new and improved magnetic means for extinguishing an arc between separable contact elements.

A further object of this invention is to provide magnetic means for the above purpose which shall be of simple, durable, and inexpensive construction.

It is a still further object of the present invention to provide magnetic blowout means for the separable contacts of an electric switch which shall be relatively small in size and easily mounted within a limited space.

It is another object of the invention to arrange electric arc extinguishing magnetic blowout means in connection with electric switch contacts in such manner as to obtain an optimum effect in lengthening and deionization of the electric arc.

It is a still further object of my invention to provide a magnetic blowout means for an electric arc which shall tend to draw the arc toward the moving contact and away from the stationary switch parts.

To the attainment of the above and other objects my invention preferably comprises a small permanent magnet of relatively high coercive force mounted upon the movable contact of a pair of separable contact members in such a manner that the engaging portion of the movable contact is interposed substantially between the pole pieces of the magnet thereby to set up a magnetic flux across the face of the movable contact. The magnet may conveniently, though not necessarily, be of substantially U or V-shape in the na-

ture of a horseshoe magnet, and the magnet is positioned so that its bight passes behind the movable contact while its pole faces are disposed diametrically across the face thereof. The lines of force thus set up across the face of the moving contact may be resolved into a plurality of radially displaced flux patterns having as their center a straight line between the pole pieces of the magnet. When the contacts are separated, the interaction of a magnetic field of the pattern described with the current in the arc path will force the major portion of the arc to follow the moving contact and magnet. Thus the arc will be lengthened and forced into cooler air not only by the well known magnetic blowout effect but will be further lengthened and further cooled by being made to follow the moving contact member which is itself moving into a cooler region. The advantages of such an arrangement over one in which a blowout magnet is mounted upon the fixed contact will be obvious. Where a blowout magnet is mounted upon the fixed contact the arc will be concentrated about an immovable point and the region of this point will become excessively heated. Such conditions are not favorable for deionization of the arc.

My invention will be better understood by referring now to the following detailed specification taken in conjunction with the accompanying drawing, in which Fig. 1 is a side view partly broken away of a panel-mounted multiple contact finger manually operable control switch embodying my invention; Fig. 2 is a sectional view taken along the line 2—2 of Fig. 1; Fig. 3 is an enlarged plan view of the stationary and movable contact members only; Fig. 4 is a cross-sectional view taken along the line 4—4 of Fig. 3, and Fig. 5 is an enlarged and exploded perspective view of the movable contact member and blowout magnet.

Referring now to the drawing and particularly to Figs. 1 and 2, I have shown a manually operable control switch generally similar in construction to that described and claimed in Patent 2,202,698, issued May 28, 1940, to Isaac R. Latta. The switch is mounted within a casing 10 which is attached to a support, such as the panel 11, by means of supporting bolts 12 and 13 passing through the panel. The switch itself comprises a stationary contact block 14 having a plurality of pairs of stationary contacts 15 mounted on opposite sides thereof, each pair being provided with a terminal connector 16. Between each pair of stationary contacts 15 is arranged an insulating barrier 17 provided at its lower end with a

pair of octagonal bosses 18 on one side thereof and a pair of aligned octagonal recesses on the opposite side thereof. The bosses 18 and aligned recesses are assembled in nesting relation to space the barriers, and the barriers are bolted firmly together and to a front supporting plate 19 by means of threaded tie rods 20 passing through the octagonal bosses 18. A support 19 is recessed to receive the adjacent octagonal bosses 18 and illustrates the manner in which the remainder of the barriers 17 are nested together.

Between each pair of barriers 17 two oppositely disposed movable contact members or fingers 21 are pivotally mounted upon the octagonal bosses 18, as illustrated at Fig. 2. Each movable contact finger 21 is formed of a strip of copper or other electrically conducting material resiliently connected to a rotatable cam lever 22, by means of a pin 23 and a wipe spring 24. Each contact finger 21 is electrically connected to a terminal block 25 by means of a flexible shunt 26. The movement of each pair of oppositely disposed movable contact fingers 21 is controlled by three centrally located rotatable cams 27, 28 and 29. The cams are mounted on a manually rotatable operating shaft 30 extending through the panel 11 and terminating in an operating handle 31. The cams 27 and 29 are each suitably shaped to move one contact finger 21 to a circuit closing position by engagement with one of the cam levers 22, while the cam 28 is suitably shaped to move both oppositely disposed fingers 21 to their circuit opening positions in a desired sequence by engagement with the pins 23.

Referring now particularly to Figs. 3, 4, and 5, it will be observed that the upper end of the movable contact finger 21 is provided with a disk-shaped contact button 32, the diameter of which is somewhat less than the width of the strip 21 and which is welded or otherwise suitably secured to the contact finger 21. From the foregoing description of the switch-actuating structure it will be evident that movement of the contact button 32 from its circuit-closing to its circuit-opening position is accomplished without any appreciable relative rotation of the surface of the moving contact with respect to the surface of the fixed contact. Such substantially straight line movement of the moving contact surface along a line substantially perpendicular to the fixed contact surface is accomplished in the illustrated embodiment of the invention by pivoting the moving contact at such a distance from the contact surfaces that its arcuate movement is very small compared to the length of the contact finger 21. The movable contact support 21 is notched, as at 33, on diametrically opposite sides of the contact button 32 to provide for the mounting of a generally U-shaped permanent magnet 34. It will be understood that the magnet 34 may have any suitable configuration such that its pole pieces will be disposed on opposite sides of, or otherwise substantially diametrically with respect to, the movable contact button thereby to establish radially displaced flux patterns across its face as previously described. It is not necessary for this purpose that the pole pieces embrace the contact, but a simple bar magnet disposed parallel to the contact surface will have the desired effect to some extent. Preferably, however, the magnet is of generally U-shape and magnetized in the manner of a horseshoe magnet. As best shown at Fig. 5, I prefer to form the magnet 34 as a substantially semi-circular wafer

slotted along its diametrical periphery to provide a pair of projecting pole pieces 35 and 36. As shown at Figs. 3 and 4, the magnet is mounted upon the movable contact support 21 and frictionally held in place by crimping the pole pieces 35 and 36 in the notches 33 so that the pole pieces of the magnet embrace between them the movable contact button 32.

In order to limit the physical proportions of my new and improved magnetic blowout means as much as possible, I propose to use a permanent magnet formed of a material having a relatively high coercive force in relation to its size. A suitable material for this purpose is an alloy comprising 6 to 15% aluminum, 12 to 30% nickel, about 5% copper, if desired, and the remainder of iron, such as described and claimed in Patents 1,947,274 and 1,968,569, issued February 13 and July 31, 1934, respectively, to William E. Ruder.

With the magnet 34 disposed in the manner described, it will establish, in any plane passing through both pole pieces, a plurality of curved magnetic lines of force in the familiar flux pattern shown at Fig. 3. If the pole pieces of the magnet lie near the contact surface of the movable contact, as is preferable, the greatest concentration of flux will be between the fixed and movable contacts toward the face of the movable contact. It will, of course, be understood that the entire flux will not lie in a plane perpendicular to the face of the movable contact but that a similar flux pattern will be formed in every plane passing through a straight line between the pole pieces of the magnet. Thus in a plane perpendicular to such a line the lines of force will appear to emanate radially from the magnet poles, which in the example illustrated lie at a point located approximately at the center of the movable contact button 32. As previously pointed out, the greatest concentration of lines will be on the side of the movable contact to engage the fixed contacts.

I wish to have it understood that it is not necessary that the line of intersection of the planar magnetic flux patterns lie in the contact surface of the moving contact member, and in fact I have not so shown it. It is sufficient that this line be transverse to an electric arc between the contact and be reasonably near or in the region of the movable contact surface.

In operation, when any pair of contacts is separated while carrying current, an initial arc will be set up substantially directly between the contacts, as along a line A of Fig. 4. The current path A crosses the flux lines in the plane A1 substantially at right angles and, according to well known electromagnet theory, the arc will be forced in a direction perpendicular to both the current path A and lines of force in the plane A1 as indicated by the arrow at Fig. 4. Thus the arc will approach a path B which intersects the lines of force in a plane B1 substantially at right angles. Again the arc will be forced in the direction indicated by the arrow until it follows a path C. At this point the lines of force in the plane C1 again force the arc upwardly and in the direction of the movable contacts. From a study of Fig. 4 it will now be evident that as the arc is further attenuated by continuous upward displacement, it comes progressively under the influence of lines of force which are gradually approaching the position of the lines of force in the plane H1. Thus the component of force exerted upon the arc tending to move it toward the mov-

able contact is gradually increased. It will now be evident that the arc is displaced by the magnet not only upward to attenuate it, but also in the direction of the movable contact further to attenuate it. Of course it will be understood that upward displacement of the arc is aided by heating of the air in the region lying immediately between the fixed movable contacts.

From the above description of an arc-interrupting operation it will be evident that by location of the blowout magnet 34 upon the movable contact rather than upon the fixed contact, I can force the electric arc to concentrate in the region of the movable contact. Since the movable contact, in moving from its closed circuit to its open circuit position, is continually moving into cooler air, it will be evident that the major portion of the arc is more efficiently cooled than it would be if it were permitted to concentrate in the region of the fixed contact where the surrounding air might become excessively heated. This more efficient cooling of the arc contributes to its deionization and rapid interruption. By actual test it has been found that a sample switch, in interrupting arcs up to its capacity of 75 amperes at 250 volts, possessed approximately 15% greater interrupting capacity throughout the range when the permanent magnet 34 was attached to the movable contact than when it was attached to the fixed contact.

A further advantage of my invention lies in its particular suitability to all types of switches in which it is imperative that the arc be directed away from the fixed contacts. For example, in the switch which has been shown and described, the fixed contact support 14 is of insulating material and may be detrimentally burned if exposed to a very hot arc. Also, many insulating materials, if exposed to an arc, will carbonize on the surface so that the surface becomes electrically conducting. Furthermore, the location of the terminal connectors 16 necessitates wiring of the switch in such a manner that the lead wires to the fixed contacts lie on top of the fixed contact support. It is, of course, essential that the

5 arcs be kept away from this wiring so that the wiring insulation will not be burned away. Burning of these insulating parts is avoided by my invention by drawing the arc toward the moving contact.

10 While I have shown a preferred embodiment of my invention by way of illustration, many modifications will occur to those skilled in the art and I, therefore, wish to have it understood that I intend by the appended claim to cover all such modifications as fall within the true spirit and scope of my invention.

15 What I claim as new and desire to secure by Letters Patent of the United States is:

15 In a circuit interrupter, the combination of fixed and movable contact members, each of said contact members comprising a strip of electrically conducting material and a contact button mounted thereon, the movable contact strip being wider than the attached contact button and being slotted at diametrically opposite sides of said button, manually operable means for actuating said movable contact member from a circuit-closing to a circuit opening position to separate 20 said contact buttons and establish therebetween an electric arc, and means for extinguishing said arc comprising a substantially U-shaped permanent magnet mounted upon said movable contact member with its bight disposed behind the movable contact button, the pole pieces of said magnet lying in said diametrically disposed slots with the movable contact button interposed therebetween thereby to establish across the engaging face of said movable contact button a plurality of lines of magnetic force forming a plurality of 25 radially displaced planar flux patterns intersecting on a straight line between the pole pieces of said permanent magnet, whereby the force exerted by said lines of force upon said arc forces 30 said arc to assume a curved and attenuated path of a shape tending to concentrate the major portion of said arc about said movable contact member.
